UNITED STATES PATENT OFFICE.

ARTHUR TINDLE, OF NOKOMIS, ILLINOIS.

PLAYER-PIANO REROLL STOP.

Application filed June 23, 1924. Serial No. 721,775.

To all whom it may concern:

Be it known that I, ARTHUR TINDLE, a citizen of the United States, residing at Nokomis, in the county of Montgomery and State of Illinois, have invented a new and Improved Player-Piano Reroll Stop, of which the following is a specification.

The invention relates to player pianos in which are included mechanisms air-actuated under control of a perforated music roll removably mountable upon the piano to be slowly unrolled to pass over the tracker bar for controlling the proper playing action and for being quickly re-rolled for removal and replacement, and has for its general object to provide automatically operating means for positively stopping the re-rolling action, by engagement with the music roll itself for preventing injurious "flapping" of the ends of that roll at the consummation of the said re-rolling action.

In present practice, player pianos are commonly provided with a lower operating roller and an upper removable roller readily mountable upon the piano and carrying the perforated music roll selected to be played, the rollers being positioned below and above the tracker bar over which the music roll is slowly drawn from the upper roller to and upon the lower roller during the playing action and for the purpose of controlling the playing of the piano automatically. When the playing of the roll has been completed the re-roll mechanisms are brought into action and the upper roll is rotated, at relatively high speed, for quickly re-rolling the music sheet back upon the removable roll that the same may be removed and replaced. The music rolls are each equipped with a securing hook whereby connection with the lower roller is made and when the re-roll action is consummated the high speed rotation of the upper roller continues freely for an interval of time during which the free flap carrying the said securing loop flaps freely about the roll and in space in a manner for scarring the piano and tearing the music roll.

Therefore, it is an object of my present invention to provide an automatically operating positive stop mechanism for engaging the music roll at the consummation of the re-rolling thereof, just before the final turn, to thereby effectively prevent flapping or lashing of the free end of the roll, as above related.

It is a further object of the invention to provide a simple and effective mechanism of the nature stated which is positive in its action and so cooperative with the tracker bar as to be air-actuated at just such interval of time as will effect stopping engagement with the roll at the very end of the re-roll action and at a time when interference with or a wearing upon the music notation perforations is impossible.

With the above and other objects in view, the invention still further resides in those novel details of construction, combination and arrangement of parts, all of which will be first fully described, then be particularly pointed out in the appended claims, and illustrated in the accompanying drawings, in which:

Figure 1 is a diagrammatic front elevation showing the application of the invention to the cooperative parts of a player piano, the parts being about to function to effect stop action.

Figure 2 is a rear elevation of the parts as shown in Figure 1.

Figure 3 is a cross section illustrating the invention at the normal, stop lever lifted, playing position.

Figure 4 is a view similar to Figure 3 illustrating the stop lever applied position, the pneumatic portions being shown in elevation.

Figure 5 is a detail perspective view of the guide and bearing bar member.

Figure 6 is a view similar to Figure 5 of the stop lever carrying slide.

Figure 7 is a perspective view illustrating the hook-and-notch hanging means for removably supporting the pneumatic.

Figure 8 is a diagrammatic elevation illustrating the movements of the cutoff valve operating levers at the rear of the spool case.

Figures 9 and 10 are detail sections illustrating the open and closed position of the cutoff valve.

Figure 11 is a central vertical cross section of the cutoff valve.

Figure 12 is an enlarged detail side elevation of the stop lever mechanism, the carrying slide therefor being shown in section.

Figure 13 is a plan view of the parts shown in Figure 12, the carrying slide being shown in section.

Figure 14 is a detail perspective view

illustrating one of the securing ends of a stop strip.

Figure 15 is a diagrammatic perspective view illustrating a modified cooperative connection between the cutoff valve and re-roll lever.

Figure 16 is a detail perspective view of the main lever of the stop mechanism.

The construction of my invention is such that it may be readily embodied in cooperation with any of the standard types of player pianos and in these drawings so much of the associated mechanism of a player piano is diagrammatically illustrated as is necessary to show the position and manner of mounting my said invention in cooperative relation therewith.

In the drawings, 1 generally indicates the spool case, which includes the vertical rear wall 2 and the side walls 3.

The usual tracker bar 4 is provided and properly secured to the tracker head 5 carried by the rear and side walls of the spool case. The tracker bar is provided with the usual air ports or apertures 6 and is also provided with a special port or aperture 7 which is located adjacent the right end of the said tracker bar beyond the position of the nearest adjacent music port, thus being in a position for being covered by the music strip wound on the music roll without possibility of the same being uncovered by any of the music perforation of the said strip.

The side walls 3 serve to support the shaft sections of the lower transmission devices which are adapted to removably receive the music roll 8. The said side walls also serve to support the power transmission shafting of the take-up roll 9, and it will be observed from the figures of the drawings that the arrangement of the music roll tracker bar and take-up roll are the same as is common in structures of the general type stated.

It should be here stated that the power transmission devices for affecting the rotation of the music and take-up rolls during the playing interval and, when reversed, for effecting the re-roll function, may be of any of the common types now in use and as the said mechanism, per se, forms no part of the present invention, it is but generally indicated, as to position in the drawings, and not further described in detail, it being deemed unnecessary for the purpose of clear disclosure. It will be observed from Figures 1 and 2 of the drawings that a relatively heavy balance wheel 10 is mounted upon one of the power transmission shaft sections for the music roll and the said wheel is provided for the purpose of insuring easy and steady re-rolling of the music strip and for preventing the blank paper from bouncing and exposing the air port 7. While, as above stated, the power transmission mechanisms,

per se, form no part of the present invention, it will be understood that all of such mechanisms usually include a pivoted re-roll lever for changing the position of the transmission elements to effect either the playing or the re-rolling of the music strip and in the drawings I have diagrammatically illustrated such a lever, it having a function in cooperation with the elements of my invention, and the said lever is indicated by the numeral 11.

The take-up roll 9 is provided with the usual cut-out portion 12 and the securing hook 13 which is adapted to receive the securing ring 14 secured to the converging point of the converging flap 15 at the free end of the music strip.

The converging end of the music strip 15, just above described, is provided on all the standard types of music rolls and it is the purpose of my present invention to prevent lashing and tearing of this end of the music roll in the manner common during the re-rolling action on player pianos commonly equipped. As the securing ring 14 leaves the securing hook 13 of the take-up roll 9, the converging end 15 of the music roll is free to flap around with the music roll 8, which is rotating at a relatively high speed, thus causing the said end to flap around against the tracker bar and spool case walls with the result of scarring of the said spool case and frequent tearing of the music roll. When a portion of the converging flap 15 of the music roll and its securing ring 14 are torn from the said roll, the roll is obviously rendered useless and as this is a common occurrence in player pianos not equipped with my invention, great waste is effected. The advantages of an automatic stop device, such as will prevent lashing at the end of the music roll, is therefore obvious.

To provide for the mounting of my invention in cooperative relation with the parts hereinbefore described, the rear wall 2 of the spool case is provided with a vertically extending slotway 16 formed in the upper edge thereof. A metal brace plate 17 is secured to the rear wall 2, is angled to fit a portion of the tracker head and the upper edge of the rear wall and slotted to register with the slot 16 of the rear wall, see Figures 3, 4 and 5. The plate 17 is provided at its upper end with guide fingers 18 which are bent back upon the said plate to form guides between the same and the said plate. The guide thus formed serves to effect the removable mounting of a centrally slotted lever supporting slide 19 which is provided with forwardly bent and apertured pivot ears 20, see Figures 4, 6 and 12.

The ears 20 of the supporting slide 19 serve to accommodate the main pivot pin 21 upon which the main lever 22 of the stop

lever mechanism is mounted. The said main lever 22 is pivoted at 23 to a carrying head 24 which is slotted to provide upper and lower side walls, between the upper ones of which the pivot 23 is formed, and between the lower ones of which the pivots 25 of the stop strip carrying arms 26 are formed. The slotting of the carrying head 24 provides a central web 27 which said web 5 is extended and thread apertured to accommodate the passage of a stop set screw 28 which is adapted to engage the abutment 29 formed on the outermost one of the carrying arms 26 to adjustably limit the spread 10 position of the said arms. The main lever 22 is cut away, as at 30 to accommodate the head of the set screw 28 when the lever device is positioned as illustrated in Figure 4, see Figures 12 and 13.

20 The carrying arms 26 are each provided with a lug 31, and a flat spring 32 is positioned between the said arms in engagement with the said lugs for the purpose of yieldably spreading the arms to the limit of their 25 spread movement as controlled by the set screw 28. A stop strip 33 of felt or other suitable flexible material is carried by the spread arms 26 and the said strip is removably connected thereto through the medium 30 of the metal securing clips 34, one of which is secured to each end of the said strip and to the ends of the said arms in a removable manner, see Figures 4, 12 and 13. It will be observed more particularly from Figure 14 35 that the said clips 34 are bent from a sheet of spring metal to a substantially S-shape, thus including a clamping jaw for clamping the respective strip end and another for clamping over the end of the respective 40 carrying arm 26. It will also be observed from the said figures, that that portion of the clip which engages the said strip acutely is provided with tooth portions 35 that effectively serve to prevent any tendency of 45 slipping of the said strip when the lever device is applied, as indicated in Figure 4 of the drawings.

The main lever 22 is extended and bifurcated as at 36 to facilitate the pivotal connection 37 thereof with the pivot lever 38. The pivot lever 38 has the ends thereof pivoted at 39 and 40 to the link arms 41, between which the said lever is movable, and the centrally disposed lever arm 42 which 55 is also pivoted at 43 to the projection 44 of the head 24.

The main lever 22 is also extended and bifurcated at 45 to permit passage of the centrally disposed lever arm 42 and to provide for the pivot connection 46 thereof with the operating arm 47 to which the link arms 41 are also pivoted as at 48. The operating arm 47 is extended rearwardly and has pivoted thereto, as at 49, an actuating 60 sleeve 50.

It will be observed by reference to Figures 3 and 4 of the drawings, and especially to Figure 12, that the stop lever device, including all of the elements indicated by the reference numerals 19 to 50, is removable as a 70 unit from the mounting therefor provided by the plate 17.

It will also be readily understood that, the guides formed by the fingers 18 being friction guides, vertical movement of the 75 slide 19 of the stop lever device will effect adjustment of position of the said device, thus effecting the point and degree of contact of the said device with the music roll.

When the mechanism thus described is 80 operatively mounted in cooperative relation with the piano parts in the manner illustrated in Figures 1 to 4 of the drawings, the actuating sleeve 50 thereof is adapted to slidably engage the actuating rod 51, which 85 is secured as at 52 to the movable board 53 of the bellows 54 which forms a part of the pneumatic. Thus, when the pneumatic is collapsed, in a manner soon to be described, 90 and the movable part 53 thereof moved from the position shown in Figure 3 of the drawings to that illustrated in Figure 4 of the drawings, the actuating sleeve 50 will be acted upon by the rod 51 and moved to effect an application of the stop lever device, 95 or rather the stop strip 33 thereof, to the music roll, as indicated in Figure 4 of the drawings.

The pneumatic includes the main or body portion 55 and a head or cap portion 56 which is removably mounted thereupon, suitable side arms or brackets 57 being secured to the said head and provided with hanging flanges which are slotted, as at 58, 100 to engage the hanging hooks 59 carried by the rear face of the case wall 2 to provide a suitable removable support for the said pneumatic, see Figures 3 and 4, and especially Figure 7.

A cut off valve 60 is secured to the rear 110 face of the case wall 2 at a point slightly above and behind the position of the music roll 8. The valve 60 includes the rotary valve head 61 which is provided with a suitable valve passage adapted to open and close communication with the passages 62 of the said valve, and an air duct 63 is provided for communicating one of the valve passages 62 with the tracker bar air port or aperture 7. Another air duct is provided 115 for communicating the remaining air passage of the said valve with the atmospheric air chamber 65 of the pneumatic head, through the rubber tube connection 66 and the metal tube section 67 leading into the 120 said head chamber.

A pouch 68 covers the chamber 65 between the head 56 and the body 55 and a lateral chamber 69 communicates, through the 125 bleeding vent 70, with the pneumatic ex- 130

haust chamber 71 of the pneumatic body 55, through the lateral 72 provided in the said body. The head 56 is provided with a receiving pocket 73 for accommodating the end of the air line connections 74 which provide air exhausting communication from a portion, designated 75, of the piano exhausting mechanism, through the medium of the lateral 76 which matches the said pocket 73. It will be understood, of course, that the pocket 73 and the lateral 76 are in free communication with the exhaust chamber 71 of the body 55 and with the atmospheric air chamber 65 of the head 56 only through the bleeding vent 70.

The body 55 is provided with an intermediate chamber 77 which is port-connected as at 78 with the interior of the bellows 54. An apertured plate 79 serves to separate and port-connect the chambers 77 and 71, and the apertured web 80 serves to separate and port-connect the chamber 77 and the atmospheric air induction chamber 81 of the said head, which latter chamber is felt-covered as at 82 to permit the induction thereto of atmospheric air. Suitable guides are provided for guiding the double valve stem 83 which has secured thereupon the valve members 84, adapted to close and open the ports above referred to alternately, and a pouch engaged head 85.

The pneumatic, just above described, is of a common type, into the bellows of which atmospheric air is permitted to enter in the manner illustrated by arrows in Figure 3 of the drawings, and communication with the air exhausting means of the player piano, through the connections 76, 73 and 74, is closed off. It will be understood that when the supply of atmospheric air is admitted into the chamber 65 through the connections 66 and 67, the pouch 68 will engage the head 85 and force the double valves down to close off atmospheric communication through 81-82 and to open exhausting communication as above related, thus causing extensive reduction of pressure within the bellows 54 from atmospheric pressure to about seven pounds and causing atmospheric pressure from without to instantly collapse the said bellows, thus moving the movable board thereof and immediately automatically applying the top lever device.

The valve head 61 has an extension which projects through the rear wall 2 of the spool case in the manner illustrated in Figure 11 of the drawings and has secured upon the end thereof an operating lever 86 adapted to be finger engaged. It will be observed by reference to Figure 1 of the drawings that the lever 86 is positioned just above and to the rear of the music roll 8 so as to be in position for being conveniently touched, to actuate the same, by the operator when removing the said music roll, in the manner

and for the purpose later to be described. The other end of the valve 61 is provided with an actuating pin 87 adapted to be acted upon by a slot link 88 which is pivoted to the upper end of the rocking lever 89 in turn pivoted as at 90 to the case wall 2. A crank arm 91 is secured to the rockable rod of the re-roll lever 11 to be rocked thereby, and the said crank is link connected as at 92 to the lower end of the said rocking lever 89. It should be understood that the finger actuated lever 86 is adapted to actuate the valve to close the same while the lever link and crank devices 88 to 92 inclusive are adapted to act upon the valve to open the same, that is, to permit air passage through the passages 62 thereof. The slotted link 88 provides for free back movement of the lever after the valve has been opened so that when the valve has been shifted to the open position by the levers and the levers moved back to the normal position the valve will remain in the open position until closed by the finger lever 86, the slot of the link 88 permitting this free movement.

In operation, assuming the device to be in the normal position illustrated in Figure 3 of the drawings with the mechanisms of the piano operating to effect a playing of the music roll, as indicated. As will be observed from the said figure, the music strip is in the process of being wound from the music roll spool across the tracker bar 4 and upon the take-up roll 9. After the playing of the music roll strip has been completed, the operator will shift the re-roll lever 11 to set the transmission mechanisms for effecting the re-roll of the music strip from the take-up roll 9 back upon the music roll 8. It should be here understood that this action of the lever 11 will effect a back movement of the lever, link and crank devices 88 to 91 in the manner above described, that is, freely without acting upon the valve body 61. In other words, the slot of the link 88 will pass freely over the valve pin 87 without acting upon the same and thereby leaving the valve to its present open position. As the re-roll action nears the completion thereof and the converging sides of the strip end effect an uncovering of the air port 7 in the manner illustrated in Figure 1 of the drawings, atmospheric air will rush in through the said port, through the open valve, and through the connections 66 and 67 into the air chambers 65, causing pouch 68 to set the double valves 84 to close off atmospheric air induction and to open exhausting action communication to thereby effect immediate collapse of the bellows 54. This action is instantaneous and as the movable board 53 of the bellows moves toward the fixed board thereof, in the manner illustrated in Figure 4 of the drawings, the

stop lever device will be actuated to immediately bring the stop strip 33 thereof down into contact with the music strip in a manner for preventing a single additional 5 complete rotation of the music roll, thereby effectively preventing all tendency of lashing of the end of the music strip. It will be observed that the link connection 42 of the stop lever device is so pivotally related to the main lever 22 as to be in the 10 nature of a parallel lever and such as will effect movement of the levers in cooperation for maintaining the carrying head 24 in a substantially like position during the 15 whole of the range of movement of the said stop lever device, see Figures 3, 4 and 12, thus ensuring proper engagement of the stop strip 33 with the music roll strip.

The stop lever device having thus been 20 applied and served its function in preventing lashing of the free end of the music roll strip, the operator, seeking to remove and replace the played music roll, will reach forward and grasp the same, simultaneously touching the lever 86 and moving the valve to the closed position. This free movement of the valve independently of the lever, link and crank devices 88 to 92 inclusive, being permitted by the slot of the 30 link 88, and thereby closing off passage of atmospheric air and permitting the pneumatic to automatically adjust itself to the normal inflated position, thereby effects an instantaneous operation of the stop lever 35 device such as will elevate the same to the normal position illustrated in Figures 3 and 12 of the drawings. Then, of course, when the re-rolled lever 11 is moved over to the right, see Figure 8 of the drawings, 40 to thus set the power transmission devices for effecting a playing of the new music roll now applied to the piano, the lever, link and crank devices 88 to 92 inclusive will be automatically acted upon, simultaneously 45 with the setting of the power transmission devices, to effect an opening of the valve 60, such as will permit free passage through the passages 62 thereto, so that when the port 7 is again uncovered at the 50 end of the re-rolling action, the stop lever devices will be again automatically brought into action in the manner hereinbefore described.

It is a particular feature of the invention to position the air port 7 adjacent the right end of the tracker bar beyond the music perforations thereof. Thus, there will be no music perforations on the music strip in position for passing over the said 55 air port. It is desirous that the air port be so positioned that only blank paper will pass over the same for if there were any perforations in the music roll positioned for passing over the said port the stop lever 60 device would be automatically brought 65 down into engagement with the music strip during the playing thereof which, of course, is not desired. As now constructed, as the tapered flap of the music roll uncovers the said port at the end of the re-roll action, 70 the stop lever device is applied in a manner for preventing a single additional whole rotation of the music roll, thus effectively preventing all tendency to lash of the free end of the strip, and this action is so automatically effective in cooperation with that portion of the exhausting apparatus with which the devices are cooperatively connected that after the said stop lever has thus been automatically applied, the harder 75 one pumps the treadles of the piano, the firmer will the said stop lever be applied to the music strip until the said cutoff valve is finger-actuated by the lever 86, as above described.

It is also a particular feature, in addition to the main feature of providing an automatically actuated stop lever device, to provide the finger closing means for the valve and also the link, lever and crank devices 90 automatically actuated in cooperation with the re-roll lever. Obviously after the valve has been closed by the finger engaged lever 86 it is necessary that the same be returned to the open position so that the mechanism 95 may automatically function again at the end of the re-roll action. If the crank, lever and link devices were not provided, it would be possible for the operator to forget to reset the valve to the open position and the device 100 would not function; but by providing these devices, the said valve is automatically reset when the operator sets the re-roll lever to the playing position which, of course, is necessary to effect a playing of the replaced 105 roll.

The provision of the balance wheel is also a feature as it will ensure easy and steady re-rolling and will prevent the music strip from bouncing during the re-rolling action 110 and thus exposing the air port 7 which automatically controls the application of the stop lever device. This inadvertent exposing of the air port by the bouncing of the music strip would cause considerable trouble 115 as the stop lever device would be automatically actuated before the re-rolling action was completed depending on what point during that action the uncovering of the port occurred. The provision of this balance 120 wheel effectively serves to prevent all possibility of trouble, as before stated.

In Figure 15 of the drawings is illustrated a modified lever connection between the re-roll lever and the cutoff valve lever for operating the latter in cooperation with the former. In this modification, the re-roll lever 11 has the same crank portion 91 at the rear end thereof. The crank 91 is linked at 93 to the crank lever 94 which is in turn 125 130

link connected as at 95 to the rocking levers 96 connected together at 97 and each pivoted to a suitable support as at 98. The uppermost lever 96 is linked as at 99 to the lever 100 pivoted as at 101 to a suitable support and slot-link connected at 102 to the cutoff valve lever 86. This arrangement may be used as a substitute for that shown in Figure 8, if desired.

10 It is preferred that the stop lever devices be constructed of metal, such as brass, nickel, silver or aluminum to match the trimming of the piano upon which it is mounted. This, of course, is optional to the manufacturer and I do not wish to be limited to such use.

15 From the foregoing description, taken in connection with the accompanying drawings, it is thought the complete construction, 20 the manner of operation and the advantages of my invention will be readily apparent to those skilled in the art to which my invention relates.

What I claim is:

25 1. In player pianos, the combination with the music roll which includes a spool and a music sheet wound thereon, the tracker bar, the take-up roll and the means for re-rolling the music roll; of means for engaging the 30 music strip to restrain the free end thereof from flapping when released from the take-up roll, and mechanism governed by the music strip for applying said engaging means to the music roll as the end of the 35 music strip is leaving the take-up roll.

2. In player pianos, the combination with the music roll which includes a spool and a music sheet wound thereon, the tracker bar, the take-up roll and the means for re-rolling the music roll; of means for engaging the music strip to restrain the free end thereof from flapping when released from the take-up roll, mechanism governed by the music strip for applying said engaging 40 means, said mechanism including a lever system, and a pneumatic for operating the lever system, the said tracker bar having a control port connected with the pneumatic.

3. In player pianos, the combination with the music roll which includes a spool and a music sheet wound thereon, the tracker bar, the take-up roll and the means for re-rolling the music roll; of means for engaging the music strip to restrain the free end thereof 45 from flapping when released from the take-up roll, mechanism governed by the music strip for applying said engaging means, said mechanism including a lever system, a pneumatic for operating the lever system, the said tracker bar having a control port connected with the pneumatic, said music sheet having a tapered flap and said port being located to be uncovered only when said flap passes the tracker bar, said port being

adapted to be closed by the music sheet during the playing interval.

4. In player pianos, the combination with the music roll which includes a spool and a music sheet wound thereon, the tracker bar, the take-up roll and the means for re-rolling the music roll including the re-roll lever, means for engaging the music strip to restrain the free end thereof from flapping when released from the take-up roll, mechanism governed by the music strip for applying said engaging means, a cut-off valve means located adjacent the music roll by which the operator may move said valve to close it, and other means cooperative with the control lever of the re-roll mechanism for operating the cut-off valve to open the same.

5. In player pianos, the combination with the tracker bar, the take-up roll and the control lever of the rewinding mechanism, of means including a pneumatic controlled from the tracker bar for restraining the rewinding operation when the end of the roll is reached, and means for rendering operative or inoperative the said restraining means independently of the tracker bar control.

6. In player pianos, the combination with the tracker bar, the take-up roll and the control lever of the rewinding mechanism, of means including a pneumatic controlled from the tracker bar for restraining the rewinding operation when the end of the roll is reached, means for rendering operative or inoperative the said restraining means independently of the tracker bar control, said last named means comprising a cutoff valve, means operative by the control lever of the rewinding mechanism for opening said valve, and other means for closing said cutoff valve.

7. In player pianos, the combination with the music roll, the tracker bar, the take-up roll and a part of the exhausting mechanism; of a lever device having a portion adapted to engage the music roll to prevent lashing of the free end thereof, a pneumatic, connections between the pneumatic and the lever device, and means automatically brought into action just preceding the end of the re-rolling of the music roll to cause the pneumatic to move and cause application of the lever device to the music roll.

8. In player pianos, the combination with the music roll, the tracker bar, the take-up roll and a part of the exhausting mechanism; of a lever device having a portion adapted to engage the music roll to prevent lashing of the free end thereof, a pneumatic, connections between the pneumatic and the lever device, and means automatically brought into action just preceding the end of the re-rolling of the music roll to cause

the pneumatic to collapse and cause application of the lever device to the music roll.

9. In player pianos, the combination with the music roll, the tracker bar, the take-up roll and a part of the exhausting mechanism; of a removably mounted lever device having a portion adapted to engage the music roll to prevent lashing of the free end thereof, a pneumatic, connections between the pneumatic and the lever device, and means automatically brought into action just preceding the end of the re-rolling of the music roll to cause the pneumatic to move and cause application of the lever device to the music roll.

10. In player pianos, the combination with the music roll, the tracker bar, the take-up roll and a part of the exhausting mechanism; of a lever device having a portion adapted to engage the music roll to prevent lashing of the free end thereof, a pneumatic, connections between the pneumatic and the lever device, means automatically brought into action just preceding the end of the re-rolling of the music roll to cause the pneumatic to move and cause application of the lever device to the music roll, and a balance wheel associated with the music roll to effect even re-rolling of the said music roll.

11. In player pianos, the combination with the music roll having a tapered end, the tracker bar, the take-up roll, and a part of the exhausting mechanism; of a lever device having a portion adapted to engage the music roll to prevent lashing of the tapered free end thereof, a pneumatic, connections between the pneumatic and the lever device, and means including an air duct opened by the tapered end of the music roll just preceding the end of the re-roll action for causing the pneumatic to move and effect application of the lever to the music roll.

12. In player pianos, the combination with the music roll having a tapered end, the tracker bar, the take-up roll, and a part of the exhausting mechanism; of a lever device having a portion adapted to engage the music roll to prevent lashing of the tapered free end thereof, a pneumatic, connections between the pneumatic and the lever device, and means cooperative with the part of the exhausting mechanism and including an air duct opening through and at the right hand end of the tracker bar and adapted to be uncovered by the tapered end of the music roll just prior to completion of the re-rolling thereof for causing the pneumatic to collapse and effect application of the lever device to the music roll.

13. In player pianos, the combination with the music roll having a tapered end, the tracker bar, the take-up roll, and a part of the exhausting mechanism; of a lever device having a portion adapted to engage the

music roll to prevent lashing of the tapered free end thereof, a pneumatic, connections between the pneumatic and the lever device, means including an air duct opened by the tapered end of the music roll just preceding the end of the re-roll action for causing the pneumatic to move and effect application of the lever device to the music roll, and manually actuated means for effecting return to normal of the pneumatic and the said lever device.

14. In player pianos, the combination with the music roll having a tapered end, the tracker bar, the take-up roll, and a part of the exhausting mechanism; of a lever device having a portion adapted to engage the music roll to prevent lashing of the tapered free end thereof, a pneumatic, connections between the pneumatic and the lever device, means cooperative with the part of the exhausting mechanism and including an air duct opening through and at the right hand end of the tracker bar and adapted to be uncovered by the tapered end of the music roll just prior to completion of the re-rolling thereof for causing the pneumatic to collapse and effect application of the lever device to the music roll, and manually actuated means for effecting return to normal of the pneumatic and the said lever device.

15. In player pianos, the combination with the music roll having a tapered end, the tracker bar, the take-up roll, the rotation transmission and the control lever therefor, and a part of the exhausting mechanism; of a lever device having a portion adapted to engage the music roll to prevent lashing of the tapered free end thereof, a pneumatic, connections between the pneumatic and the lever device, means cooperative with the part of the exhausting mechanism and including an air duct opening through and at the right hand end of the tracker bar and adapted to be uncovered by the tapered end of the music roll just prior to completion of the re-rolling thereof for causing the pneumatic to collapse and effect application of the lever device to the music roll, a cutoff valve associated with the air duct, means for closing the valve to restore the pneumatic to normal, and means moved by the transmission control lever for opening the valve.

16. In player pianos, the combination with the music roll, the tracker bar, the take-up roll and a part of the exhausting mechanism; of a lever device having a stop strip portion removably interchangeably mounted thereon and adapted to engage the music roll to prevent lashing of the free end thereof, a pneumatic, connections between the pneumatic and the lever device, and means automatically brought into action just preceding the end of the re-rolling of the

music roll to cause the pneumatic to move and cause application of the lever device to the music roll.

17. In player pianos, the combination with the music roll, the tracker bar, the take-up roll and a part of the exhausting mechanism; of a removably mounted lever device having a stop strip portion removably interchangeably mounted thereon and adapted to engage the music roll to prevent lashing of the free end thereof, a pneumatic, connections between the pneumatic and the lever device, and means automatically brought into action just preceding the end of the re-rolling of the music roll to cause the pneumatic to collapse and cause application of the lever device to the music roll.

18. In player pianos, the combination with the music roll having a tapered end, the tracker bar, the take-up roll and a part of the exhausting mechanism; of a lever device having a portion adapted to engage the music roll to prevent lashing of the tapered free end thereof, a pneumatic, connections between the pneumatic and the lever device, means cooperative with the part of the exhausting mechanism and including an air duct opening through and at the right hand end of the tracker bar and adapted to be uncovered by the tapered end of the music roll just prior to completion of the re-rolling thereof for causing the pneumatic to collapse and effect application of the lever device to the music roll, a cut-off valve connected in the air duct, a hand lever for closing the valve, lever and link devices associated with the valve and the transmission control lever for being moved by the latter to effect an opening of the valve.

19. In player pianos, the combination with the music roll having a tapered end, the tracker bar, the take-up roll, and a part of the exhausting mechanism; of a lever device having a portion adapted to engage the music roll to prevent lashing of the tapered free end thereof, a pneumatic, connections between the pneumatic and the lever device, means cooperative with the part of the exhausting mechanism and including an air duct opening through and at the right hand end of the tracker bar and adapted to be uncovered by the tapered end of the music roll just prior to completion of the re-rolling thereof for causing the pneumatic to collapse and effect application of the lever device to the music roll, a cutoff valve connected in the air duct, a hand lever located at a point readily accessible to the hand of the operator when removing the music roll and movable for closing the valve, and lever and link devices associated with the valve and the transmission control lever for being moved by the latter to effect an opening of the valve.

20. In player pianos, the combination

with the music roll having a taper end, the tracker bar, the take-up roll, and a part of the exhausting mechanism; of a lever device having a portion adapted to engage the music roll to prevent lashing of the tapered free end thereof, a pneumatic, connections between the pneumatic and the lever device, means cooperative with the part of the exhausting mechanism and including an air duct opening through and at the right hand end of the tracker bar and adapted to be uncovered by the tapered end of the music roll just prior to completion of the re-rolling thereof for causing the pneumatic to collapse and effect application of the lever device to the music roll, a cut off valve connected in the air duct, a hand lever for closing the valve, lever and link devices associated with the valve and the transmission control lever for being moved by the latter to effect an opening of the valve, the said lever and link devices including a slotted link for engaging the valve for moving it when moved in one direction and for permitting free movement without valve action in the opposite direction.

21. In player pianos, the combination with the music roll, the tracker bar, the take-up roll and a part of the exhausting mechanism; of a lever device adapted to be moved to engage the music roll to prevent free flapping of the end thereof; the said lever device including a main pivoted lever, a carrying head secured to the main lever, carrying arms spread connected to the head, and a stop strip extended across the arms and adapted to engage the music roll; a pneumatic, connections between the pneumatic and the lever device, and means for causing the pneumatic to collapse and effect an application of the lever device.

22. In player pianos, the combination with the music roll, the tracker bar, the take-up roll and a part of the exhausting mechanism; of a lever device adapted to be moved to engage the music roll to prevent free flapping of the end thereof; the said lever device including a main pivoted lever, a carrying head secured to the main lever, carrying arms spread connected to the head, and a stop strip extending across the arms and adapted to engage the music roll; a pneumatic, connections between the pneumatic and the lever device, and means automatically brought into action just preceding the finish of the re-rolling of and controlled by the passing of the music roll to cause the pneumatic to collapse and effect application of the said lever device.

23. In player pianos, the combination with the music roll, the tracker bar, the take-up roll and a part of the exhausting mechanism; of a lever device adapted to be moved to engage the music roll to prevent free flapping of the end thereof; the

6 said lever device including a main pivoted lever, a carrying head secured to the main lever, carrying arms spread connected to the head, and a stop strip extended across and removably interchangeably connected to the arms and adapted to engage the music roll; a pneumatic, connections between the pneumatic and the lever device, and means for causing the pneumatic to collapse and effect an application of the lever device.

15 24. In player pianos, the combination with the music roll, the tracker bar, the take-up roll and a part of the exhausting mechanism; of a lever device adapted to be moved to engage the music roll to prevent free flapping of the end thereof; the said lever device including a main pivoted lever, a carrying head secured to the main lever, carrying arms spread connected to the head, set screw and spring devices for governing and maintaining the spread condition of the arms, and a stop strip extended across and removably interchangeably connected to the arms and adapted to engage the music roll; a pneumatic, connections between the pneumatic and the lever device, and means for causing the pneumatic to collapse and effect an application of the lever device.

25 25. In player pianos, the combination with the music roll, the tracker bar, the take-up roll and a part of the exhausting mechanism; of a lever device adapted to be moved to engage the music roll to prevent free flapping of the end thereof; the said lever device including a main pivoted lever, a carrying head secured to the main lever, carrying arms spread connected to the head, set screw and spring devices for governing and maintaining the spread condition of the arms, and a stop strip extended across and removably interchangeably connected to the arms and adapted to engage the music roll; a pneumatic, connections between the pneumatic and the lever device, and means for causing the pneumatic to collapse and effect an application of the lever device.

35 26. In player pianos, the combination with the music roll, the tracker bar, the take-up roll and a part of the exhausting mechanism; of a lever device adapted to be moved to engage the music roll to prevent free flapping of the end thereof; the said lever device including a main pivoted lever, a carrying head secured to the main lever, carrying arms spread connected to the head, a stop strip extended across the arms and adapted to engage the music roll, and a parallel link connection between main lever and carrying head for holding the latter to relatively same position throughout its movement; a pneumatic, connections between the pneumatic and the lever device, and means for causing the pneumatic to collapse and effect an application of the lever device.

45 27. In player pianos, the combination with the music roll, the tracker bar, the take-up

50 roll and a part of the exhausting mechanism; of a lever device adapted to be moved to engage the music roll to prevent free flapping of the end thereof; the said lever device including a main pivoted lever, a carrying head secured to the main lever, carrying arms spread connected to the head, set screw and spring devices for governing and maintaining the spread condition of the arms, a stop strip extended across and removably interchangeably connected to the arms and adapted to engage the music roll, and a parallel link connection between main lever and carrying head for holding the latter to relatively same position throughout its movement, a pneumatic, connections between the pneumatic and the lever device, and means for causing the pneumatic to collapse and effect an application of the lever device.

55 28. In player pianos, the combination with the music roll, the tracker bar, the take-up roll and a part of the exhausting mechanism; of a lever device adapted to be moved to engage the music roll to prevent free flapping of the end thereof; the said lever device including a main pivoted lever, a carrying head secured to the main lever, carrying arms spread connected to the head, and a stop strip extended across the arms and adapted to engage the music roll; a removably mounted slide having apertured ears forming pivotal connection for the lever device, a pneumatic, connections between the pneumatic and the lever device, and means for causing the pneumatic to collapse and effect an application of the lever device.

60 29. In player pianos, the combination with the music roll, the track bar, the take-up roll and a part of the exhausting mechanism; of a lever device adapted to be moved to engage the music roll to prevent free flapping of the end thereof; the said lever device including a main pivoted lever, a carrying head secured to the main lever, carrying arms spread connected to the head, set screw and spring devices for governing and maintaining the spread condition of the arms, a stop strip extended across and removably interchangeably connected to the arms and adapted to engage the music roll, and a parallel link connection between main lever and carrying head for holding the latter to relatively the same position throughout its movement; a removably mounted slide having apertured ears forming pivotal connection for the lever device, a pneumatic, connections between the pneumatic and the lever device, and means for causing the pneumatic to collapse and effect an application of the lever device.

65 30. In player pianos, the combination with the spool case wall, the music roll, the tracker bar, the take-up roll and a part of the exhausting mechanism; of a lever de-

vice having a portion adapted to engage the music roll to prevent lashing of the free end thereof, a pneumatic, connections between the pneumatic and the lever device, and means automatically brought into action just preceding the end of the re-rolling of the music roll to cause the pneumatic to move and cause application of the lever device to the music roll, slotted bracket arms secured to the pneumatic, and hooks carried by a part of the spool case wall and adapted to fit the slots of the bracket arms to removably hang the said pneumatic.

31. In player pianos, the combination with the music roll which includes a spool and a music sheet wound thereon, the tracker bar, the take-up roll and the means for re-rolling the music roll including the re-roll lever; of means for engaging the music strip to restrain the free end thereof from flapping when released from the take-up roll, mechanism governed by the music strip for applying said engaging means, a cutoff valve, means located adjacent the music roll by which the operator may move said valve to close it, and other means cooperative with the control lever of the re-roll mechanism for operating the cutoff valve to open the same, the said other means acting on the valve when moved in one direction only.

32. In player pianos, the combination with the music roll which includes a spool and a music sheet wound thereon, the tracker bar, the take-up roll and the means for re-rolling the music roll including the re-roll lever; of means for engaging the music strip to restrain the free end thereof from flapping when released from the take-up roll, mechanism governed by the music strip for applying said engaging means, a cutoff valve, means located adjacent the music roll by which the operator may move said valve to close it, other means cooperative with the control lever of the re-roll mechanism for operating the cutoff valve to open the same, the said other means acting on the cutoff valve only when the said control lever is moved to the re-playing position and moving freely when the said lever is moved to the re-rolling position.

33. In player pianos, the combination with the music roll, the tracker bar, the take-up roll and a part of the exhausting mechanism; of a vertically adjustably mounted lever device having a portion adapted to engage the music roll to prevent lashing of the free end thereof, a pneumatic, connections between the pneumatic and the lever device, and means automatically brought into action just preceding the end of the re-rolling of the music roll to cause the pneumatic to move and cause application of the lever device to the music roll.

34. In player pianos, the combination with

the music roll, the tracker bar, the take-up roll and a part of the exhausting mechanism; of a vertically adjustably and removably mounted lever device having a portion adapted to engage the music roll to prevent lashing of the free end thereof, a pneumatic, connections between the pneumatic and the lever device, and means automatically brought into action just preceding the end of the re-rolling of the music roll to cause the pneumatic to move and cause application of the lever device to the music roll.

35. In player pianos, the combination with the music roll having a tapered end, the tracker bar, the take-up roll, the control lever of the rotation transmission mechanism, and a part of the exhausting mechanism; of a lever device having a portion adapted to engage the music roll to prevent lashing of the tapered free end thereof, a pneumatic, connections between the pneumatic and the lever device, means including an air duct opened by the tapered end of the music roll just preceding the end of the re-roll action for causing the pneumatic to move and effect application of the lever device to the music roll, and manually actuated means for effecting return to normal of the pneumatic and the said lever device, and other means cooperative with the control lever of the rotation transmission mechanism for resetting the valve to normal automatically.

36. In player pianos, the combination with the music roll having a tapered end, the tracker bar, the take-up roll, the control lever of the rotation transmission mechanism, and a part of the exhausting mechanism; of a lever device having a portion adapted to engage the music roll to prevent lashing of the tapered free end thereof, a pneumatic, connections between the pneumatic and the lever device, means cooperative with the part of the exhausting mechanism and including an air duct opening through and at the right hand end of the tracker bar and adapted to be uncovered by the tapered end of the music roll just prior to completion of the re-rolling thereof for causing the pneumatic to collapse and effect application of the lever device to the music roll, manually actuated means for effecting return to normal of the pneumatic and the said lever device, and other means cooperative with the control lever of the rotation transmission mechanism for resetting the valve to normal automatically.

37. In player pianos, the combination with the music roll, the tracker bar, the take-up roll and a part of the exhausting mechanism; of a lever device adapted to be moved to engage the music roll to prevent free flapping of the end thereof; the said lever

device including a main pivoted lever, a carrying head secured to the main lever, carrying arms spread connected to the head, and a stop strip extended across the arms and adapted to engage the music roll; a removably and adjustably mounted slide having apertured ears forming pivotal connection

for the lever device, a pneumatic, connections between the pneumatic and the lever device, and means for causing the pneu- 10 matic to collapse and effect an application of the lever device.

ARTHUR TINDLE.
